(57) **CLAIM**

The ornamental design for a sensor node, as shown and described.

DESCRIPTION

FIG. 1 is a front perspective view of a sensor node showing the claimed design.

FIG. 2 is a rear perspective view of the sensor node.

FIG. 3 is a front view of the sensor node.

FIG. 4 is a rear view of the sensor node.

FIG. 5 is a left side view of the sensor node.

FIG. 6 is a right side view of the sensor node.

FIG. 7 is a bottom view of the sensor node; and,

FIG. 8 is a top view of the sensor node.

The broken lines in the drawings illustrate portions of the sensor node that form no part of the claimed design.
